LOADING DEVICE

Milburn A. Hollengreen and William E. Happel,
Waynesboro, Pa., assignors to Landis Tool Company, Waynesboro, Pa.

Application December 8, 1948, Serial No. 64,156

6 Claims. (Cl. 51—103)

1

This invention relates to a loading apparatus and method for introducing work pieces, such as anti-friction bearing rings, into a centerless grinding throat.

Previous methods and devices for performing this function usually required that the work be pushed into the grinding throat either manually or by a power-operated pushing device. None of these have met with any great success. One essential characteristic of a device of this type is that it feeds the work to the grinding throat at substantially the same rate that the regulating wheel feeds the work through the grinding throat. We propose to meet this requirement in a manner which is directly opposite to that used in previous attempts to make loading devices for this kind of work. Instead of pushing the work to the grinding throat, we propose to use the feeding action of the regulating wheel to pull the work into the throat as well as to feed it through the throat.

It is, therefore, an object of this invention to provide means whereby the work pieces may be held closely face to face both before and after entering the grinding throat.

A further object is to magnetize the work pieces before introducing them into the grinding throat.

A further object is to provide means for demagnetizing the work pieces after they leave the grinding throat.

The drawing shows the conventional centerless grinding throat provided between a peripherally opposed grinding wheel 10 and regulating wheel 11. The work pieces 12 are supported between the wheels in the conventional manner on a work rest blade (not shown). A magnetizing coil 15 is mounted at the entrance end of the grinding throat and may be energized by any suitable source of direct current. A tube 18 serves to guide the work pieces through said coil and toward said grinding throat.

The control wheel is wider than the grinding wheel and its operative surface extends beyond that of the grinding wheel at the entrance end of the grinding throat. A spring pressed roller 17 is mounted opposite this portion of the control wheel and above the center of the work to hold the work against the work rest and the control wheel. When a series of work pieces is started toward the throat, this action of roller 17 causes the rotation of the work prior to entering the throat. After the work enters the throat, all the magnetized pieces in or out of the throat continue to rotate due to the action of the grinding and control wheels. Said roller is still needed to hold

the work on the rest prior to entering the throat.

A demagnetizing coil 16 is mounted at the exit end of the grinding throat and may be energized by any suitable source of alternating current. A tube 19 conducts finished work pieces from the grinding throat through said demagnetizing coil 16.

When coil 15 is energized and a series of work pieces are passed therethrough, said work pieces become magnetized and adhere to one another. To start the grinding operation, the operator pushes the work pieces through the magnetizing coil until the first one enters the grinding throat. A certain amount of feeding action is also provided by coil 15 in that it tends to hold all the work pieces within the magnetic field in a predetermined position. When this condition is disturbed, such as by adding new pieces, the magnetic field tends to maintain its balance and in so doing advances the succession of work pieces toward the grinding throat.

Thereafter, the regulating wheel takes up the rotation and feeding of the work; and the work pieces outside the throat are rotated and moved endwise along with those in the throat. Thus, it may be said that the regulating wheel pulls the work into the throat as well as causes it to pass through the throat.

After the work has been ground, it passes from the grinding throat through the demagnetizing coil. As the work leaves the demagnetizing coil, it is again separated into individual pieces. This method causes the work pieces to be held square relative to one another before entering the grinding throat as well as during the passage through the grinding throat. When so held, there is very little chance, if any, of the work's being ground tapered.

We claim:

- 40 1. In a centerless grinding machine, peripherally opposed grinding and control wheels, a work rest for supporting work pieces in operative relation to said wheels, means for magnetizing work pieces before introducing them between said wheels, said magnetizing means being effective to advance said work pieces toward said wheels as additional work pieces are added and causing them to adhere to one another whereby to hold them square with each other and cause them to rotate as a unit when acted upon by the control wheel and the grinding wheel during the grinding operation.
- 45 2. In a centerless grinding machine, peripherally opposed grinding and control wheels, a work rest for supporting work pieces in opera-

tive relation to said wheels, means for magnetizing work pieces before introducing them between said wheels, said magnetizing means being effective to advance said work pieces toward said wheels as additional work pieces are added and causing them to adhere to one another whereby to hold them square with each other and with the grinding wheel during the grinding operation, means for tilting said control wheel to move said work pieces as a unit past said grinding wheel, and means for demagnetizing said work pieces as they pass from between said wheels.

3. The method of introducing ringlike work pieces into the throat of a centerless grinding machine having peripherally opposed grinding and control wheels and a work rest for supporting work pieces in operative relation to said wheels and in which the axis of the control wheel is tilted relative to the axis of the grinding wheel which consists in magnetizing said work pieces so that they adhere to one another and thereby produce the effect of a single elongated work piece which may be held substantially square with said grinding wheel during a grinding operation, advancing the work pieces axially toward the grinding throat by the action of the magnetizing means, feeding said work pieces through the throat as a unit by the action of the control wheel, and thereafter demagnetizing said work pieces.

4. The method of introducing ringlike work pieces into the throat of a centerless grinding machine having peripherally opposed grinding and control wheels and a work rest for supporting work pieces in operative relation to said wheels and in which the axis of the control wheel is tilted relative to the axis of the grinding wheel which consists in magnetizing said work pieces so that they adhere to one another and thereby produce the effect of a single elongated work piece which may be held substantially square with said grinding wheel during a grinding oper-

ation, introducing said work pieces from said magnetizing means into said grinding throat, feeding said work pieces through said grinding throat as a unit by the feeding action of the control wheel, and thereafter demagnetizing said work pieces.

5. In a centerless grinding machine, peripherally opposed grinding and control wheels, a work rest for supporting work pieces in operative relation to said wheels, means for magnetizing work pieces before introducing them between said wheels comprising a magnetizing coil adjacent the entrance to the grinding throat formed between said wheels, means for passing a succession of work pieces through said coil and into the grinding throat, this movement being assisted by the action of the coil in causing the succession of work pieces to advance each time additional work pieces are added, said coil also causing said work pieces to become magnetized so as to adhere to one another, whereby they are caused to rotate as a unit when acted upon by the grinding and control wheels.

6. In a machine tool in which rough work pieces are introduced at one point and are discharged in finished condition at another point, means for holding ringlike members in position for a machining operation, comprising a guide means for directing said work pieces into the machine, a magnetizing coil surrounding said guide means for magnetizing said work pieces so that they will adhere to one another during the machining operation, additional guide means at the discharge point on the machine for conducting finished work pieces away from the machine, and a coil surrounding said guide means for demagnetizing said work pieces.
